UNITED STATES PATENT OFFICE.

JOHN D. THOMPSON, OF ROCHESTER, NEW YORK.

SIGNAL.

1,312,217.

Specification of Letters Patent.

Patented Aug. 5, 1919.

Application filed October 17, 1917. Serial No. 196,987.

To all whom it may concern:

Be it known that I, JOHN D. THOMPSON, a subject of the King of Great Britain and Ireland, residing at Rochester, county of Monroe, State of New York, have invented 5 a certain new and useful Improvement in Signals, and declare the following to be a full, clear, and exact description of the same, such as will enable others skilled in the art 10 to which it pertains to make and use the same, reference being had to the accompanying drawings, which form a part of this specification.

My invention relates to a signal apparatus 15 for automobiles.

In the accompanying drawings:

Figure 1 is a perspective of a portion of the forward part of an automobile with a signal apparatus embodying my invention 20 attached thereto.

Fig. 2 is a detached view of the signal apparatus partly in section and a part being removed to show the interior construction, the electrical circuits being shown in 25 diagram.

Fig. 3 is a section on the line B—B Fig. 2.

Fig. 4 is a detail view of the signal operating mechanism, the front of the containing casing being removed.

Fig. 5 is a view similar to Fig. 4 with the door open to permit the passage of the signal.

D is the body of an automobile; E is the wind-shield and F the steering wheel.

a is a movable part constituting the signal proper. This is made of translucent material and is shaped and marked to resemble a human hand. Within the signal, or hand, a is an incandescent lamp b.

e is a box, or casing, into which the signal a may turn and be concealed from view. The casing e is provided with a door o at its lower edge which may be opened, as shown in Figs. 2, 3 and 5, to permit the 45 exit of the hand, or signal, a or which may be closed, as shown in Figs. 1 and 4.

The hand a is pivoted at one end upon a pintle c which extends from the back wall of the casing e. Upon the hand a is a small gear wheel c² which passes over the pintle c and is rigidly secured to the hand. d is a segmental gear pivoted at d² to the casing e in a plane parallel to the plane of rotation of the signal a. The teeth of the segment d engage those of the gear wheel c² upon the casing e so that the oscillation of said seg-

mental gear shall turn the gear wheel c² and therefore the signal a. g is a drag link pivoted at one end to the segmental gear d below its pivot, and guided so as to reciprocate horizontally in a socket piece g⁵ at the other end. g² is a spring on the casing e tending to force the drag link g to the right in the position at which the signal a is folded within the casing e. g⁴ is a stop upon the drag link g limiting the motion of the same toward the right. g³ is an engaging surface, or tooth, on the drag link g. f is a lever pivoted at one end to the back wall of the casing e near the outer end thereof 60 and extending horizontally adjacent to the lower edge of said casing. f² is a spring acting to raise the lever f. f² is a pawl secured to the lever f and adapted to engage the tooth g³ on the drag link g at one position of the latter.

o is a door hinged at the lower edge of the rear wall of the casing e and adapted to close the otherwise open lower portion of said casing. p is a link or connecting rod 70 pivoted at p² to a lug at the free end of the lever f and at its other end pivoted to a lug on the door o. When the lever f rises it pulls the door o to closed position by means of the link p.

m is a bell crank lever pivoted at m² to the drag link g. One arm of the lever m extends horizontally past the engaging surface g³ on said link. The other arm of the lever m extends vertically to a point above 80 the drag link g.

h is a connecting rod pivoted at m² to the upper end of the vertical arm of the bell crank lever m. h³ is a cord, or chain, attached to the otherwise free end of the connecting rod h.

s s² is a tube having a vertical portion s and a horizontal portion s² extending from the upper end of the vertical portion s.

The cord h³ passes into the tube s s² over 100 the guide pulleys h² h² and out of an opening toward the lower end of the portion s of said tube. i is a lever pivoted on a lug upon the tube s s² and extending over the opening at the lower end of said tube through which the cord h³ passes, said cord is secured to the lever i. i² is a spring acting to force the lever i away from the tube s. i³ is an engaging hook pivoted to the lever i and adapted to engage an edge i⁴ on the tube s. The hook i³ has an arm extending at right angles from its pivoted end. i⁵ are two contact points,

one on the arm extending from the hook i^3 , the other on the lever arm i .

n is a source of electrical current which may be a battery. j is a horn. j^2 j^2 j^2 are conductors forming a circuit in which is the battery n and the horn j which circuit may be completed through the contact points i^5 to sound the horn.

k^2 indicates contact points that are in a circuit k k including the battery n . When the signal a is thrown to its outer position the circuit k k is completed through the lamp b at the contact k^2 so as to light the lamp.

The operation of the above described device is as follows:

When the hook i^3 is released from engagement with the edge i^4 the lever i is forced by the spring i^2 to its outer position, as shown in Figs. 1 and 2, thus drawing through the cord h^3 , rod h , the link g to its position farthest to the left, oscillating the segmental gear d and turning the hand or signal a to its outer and exposed position, as shown in Figs. 1 and 2. When this is done the circuit is completed through the lamp b and the translucent hand constituting the signal is illuminated so as to be distinctly seen at night.

At the first motion outward of the lever arm i the bell crank lever m is oscillated about its pivot m^4 thus pressing downward on the pawl f^2 and forcing the lever f to its lower positions (Figs. 4 and 5) thus opening the door o to give passage to the hand when being turned to its outer position as above described. When the drag link g is drawn toward the lever the end of the pawl f^2 engages against its lower surface (Fig. 2) and holds the lever arm f down and the door open.

When it is desired to withdraw the signal a the lever arm i is pressed inward until the hook i^3 engages the edge i^4 on the tube s . This releases the tension on the cord h^3 and the spring g^2 forces the link g to the right oscillating the segmental gear d and turning the hand or signal a into the casing e . When the link g has passed to near the limit of its travel to the right the pawl f^2 is just beyond the lower edge of said link and comes to engagement against the outer end of the horizontal arm of the bell crank lever m . The spring f^3 then raises the link f oscillating the bell crank lever m and bringing the pawl f^2 in engagement with the tooth or engaging portion g^3 of the link g , and the raising of the link f closes the door o .

The pawl f^2 engaging the portion g^3 prevents the longitudinal movement of the link g and thus locks the apparatus in the closed position of the casing and it can only be unlocked by oscillating the lever m .

When the driver wishes to display the signal he first disengages the hook i^3 from the edge i^4 and in so doing brings the points i^5

into contact with each other completing the circuit through the horn j and sounding an alarm. He then allows the lever arm i to turn to its outer position which displays the signal a as above described.

The rear wall e^2 of the casing e is a mirror, or is provided with a mirror, which the driver may utilize to observe whether or not there is a vehicle approaching from the rear.

The apparatus is adjusted to the automobile by securing the vertical portion s of the tube s s^2 to the vertical side piece of the wind-shield by clips or otherwise, as shown in Fig. 1.

The movable part a is so constructed that when it is turned within the casing its outer end forms an inclosure to the casing.

The apparatus being actuated by opposing springs all lost motion is taken up and there is no rattling due to the motion of the vehicle.

What I claim is:

1. In an apparatus of the kind described, a casing, a pivoted signal in said casing adapted to extend beyond the same when turned in one position and to be inclosed in said casing with its outer end forming the inclosing wall to the end of said casing when turned to the other position, a door adapted to open and close a side portion of said casing to permit the passage of said signal and to inclose the same, and automatic means for locking said door when the signal is turned within said casing.

2. In an apparatus of the kind described, a casing, a pivoted signal in said casing adapted to extend beyond the same when turned in one position and to be inclosed in said casing with its outer end forming the inclosing wall to the end of said casing when turned to the other position, a door adapted to open and close a certain portion of said casing to permit the passage of said signal and to inclose the same, and automatic means for locking said door and signal when the signal is turned into said casing.

3. In an apparatus of the kind described, a casing, a movable signal part, a reciprocating rod adapted to actuate said signal part, a hinged door adapted to open and close one side of said casing, a tooth upon said reciprocating rod, a pawl connected with said door so as to engage said tooth when the door is closed, a lever pivoted upon said reciprocating rod and engaging said tube, and means connecting with said lever for reciprocating said rod so arranged that it shall disengage said tooth when the force for reciprocating the rod is applied to said lever.

4. In an apparatus of the kind described, a movable signal part, a spring acting to throw said part into its exposed position and a spring adapted to retract said signal part, and means for acting upon the last

named spring to permit the projecting spring to act, substantially as and for the purpose described.

5. In an apparatus of the kind described, a casing open on two sides, a signal in said casing adapted to swing 180 degrees and extend beyond the same when in one position and to be inclosed in said casing with its end closing one of the openings when

turned in the other position, a door adapted 10 to open and close the side opening of said casing to permit the passage of said signal and to inclose the same and automatic means for working the door independent of the signal.

15

In testimony whereof, I sign this specification.

JOHN D. THOMPSON.
